AUXILIARY SUPPORT FOR A SEAT CUSHION

Richard F. Swenson, Milwaukee, Wis., assignor to
Swenson Corporation, Redgranite, Wis., a corpora-
tion of Wisconsin

Filed Nov. 18, 1968, Ser. No. 14,523

Term of patent 14 years

Int. Cl. D6—01

U.S. Cl. D15—1

FIGURE 1 is a top, side and rear perspective view of an auxiliary support for a seat cushion embodying my new design;

FIGURE 2 is a front elevational view of the seat cushion; and

FIGURE 3 is a side elevational view thereof.

I claim:

The ornamental design for an auxiliary support for a seat cushion, substantially as shown and described.
